Primary Examiner — W. A. Teddy Falloway

(74) Attorney, Agent, or Firm — Ricky Lam

(57) **CLAIM**

The ornamental design for an incense burner, as shown and described.

DESCRIPTION

FIG. 1 is a perspective view of an incense burner showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the incense burner that form no part of the claimed design.

1 Claim, 8 Drawing Sheets
